(57) **CLAIM**

The ornamental design for combined module and cable for ultrasound system, as shown and described.

DESCRIPTION

The combined module and cable for ultrasound system provides a functional unit such as an electrocardiogram (ECG) as an extension of a medical diagnostic system such as a handheld ultrasound system.

FIG. 1 is a perspective view of the combined module and cable for ultrasound system showing my new design;

FIG. 2 is a front view thereof;

FIG. 3 is a side view thereof; and,

FIG. 4 is a top view thereof.
